LOCKING MECHANISM FOR ACCORDIONS

Stanley Olson, Chicago, Ill.

Application February 23, 1937, Serial No. 127,304

1 Claim. (Cl. 84—376)

This invention relates to locking mechanism for accordions and has for an object to provide a simplified mechanism located entirely within the instrument with the exception of an operating button on the outer face of the instrument within convenient reach of the operator's hand when playing the instrument.

A further object is to provide a locking mechanism for the bellows of accordions including interlocking hooks, one of which is provided with a spring controlled hinge intermediate the ends for maintaining the hooks normally engaged, there being a dislodging lever pivoted intermediate the ends within the accordion and terminating in a button on the exterior of the accordion which may be moved by the operator's hand to disengage the hooks easily and quickly when the instrument is to be played, and hold the hooks disengaged until it is desired to again lock the bellows closed.

A further object is to provide a mechanism for locking an accordion bellows which will be composed of a few strong simple and durable parts, which will be inexpensive to manufacture, and install, and which will not easily get out of order.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawing forming part of this specification,

Figure 1 is a side elevation of an accordion with portions broken away to expose bellows locking mechanism constructed in accordance with the invention.

Figure 2 is a plan view of the operating lever and its pivotal connections, buttons, and yielding means for holding the lever in adjusted positions.

Figure 3 is a longitudinal sectional view through the hook equipped with a hinge intermediate its ends.

Figure 4 is a bottom plan view of the hook shown in Figure 3.

Figure 5 is a front elevation of the interior face plate showing the slot and sockets therein for receiving the lever in either of its adjusted positions.

Figure 6 is a side elevation of one of the hooks.

Figure 7 is a front elevation of the sleeve member for adjustably securing the stationary hook.

Referring now to the drawing in which like characters of reference designate similar parts in the various views, 10 designates an accordion having the usual bellows 11 and usual keyboard 12. In applying the invention to the accordion 5 a pair of bellows locking mechanisms may be employed, as shown in Figures 1 and 2, arranged in superposed relation and each a duplicate of the other, although in practice a single locking mechanism may be employed if desired. 10

In carrying out the invention each bellows locking mechanism comprises a pair of interlocking hooks 13 and 14, the hook 13 being threaded for a portion of its length and inserted in a sleeve 15 having a base plate 16 which may be rigidly secured to a stationary part 17 of the accordion between two adjacent reeds. The threaded end of the hook extends through an opening in the part 17 and a pair of adjusting nuts 18 are threaded on to the hook, one of the nuts bearing against the end of the sleeve 15 and the other nut bearing against a washer 19 which abuts the stationary part 17. Manipulation of the nuts may be resorted to to adjust the length of the hook. 20

The hook 14 is provided intermediate its ends with a conventional spring pressed hinge including interleaved hinge eyes 20 and a hinge pin 21 passing through the eyes, there being a helical spring 22 sleeved on the hinge pin and having the ends 23 engaging the two members of the hook to normally hold the hook in a rectilinear condition to interengage with the hook 13. A pair of stops 24 are struck from the material of the members of the hook and extend downwardly to 35 abutting engagement with each other underneath the spring to prevent movement of the free end of the hook past a position in alignment with the fixed end of the hook, the latter being provided with an angularly directed foot 25 which is secured to a stationary part 26 of the accordion by bolts 27. 40

An operating lever 28 is provided with a ball 29 intermediate its ends, which rotatably fits in an opening 30 formed in the stationary member 26, there being gudgeons 31 on the ball which fit in openings 32 in the stationary member 26 and in sockets 33 formed in the sides of bolts 34 that are fixed to the stationary member 26 to pivotally mount the lever intermediate its ends. The ball 50 forms an air tight connection between the lever and the stationary member.

The lever is provided with a fork 35 at one end to receive the gudgeons 36 of a roller 37 which is adapted to engage the pivoted end of the hook 55

14 when the lever is rocked in one direction and dislodge the hook 14 from the hook 13 to permit opening of the bellows.

5 The outer end of the hook 28 is threaded to receive a knurled button 38 which is exposed exteriorly of the accordion in position to be shifted by the operator's hand to rock the lever on its pivot to released position or to operative position. The lever projects through a slot 39 formed in the accordion and on opposite sides of the slot are arranged plates 40 and 41 which are secured to the accordion by bolts 42 that pass through the plates.

10 The plate 41, as best shown in Figure 5, is provided with a slot 43, the ends of which are enlarged, as shown at 44 and countersinks 45 are formed around the enlarged ends to interchangeably receive the rounded end of a stop 46 which is loosely mounted on the lever. A helical spring 47 is sleeved on the lever and is confined under tension between the stop 46 and the collar 48 rigidly secured to the lever.

15 The stop 46 is yieldably received in one of the enlarged ends of the slot 43 and maintained in this position when the lever is shifted in one direction and is yieldably received in the mating slot and retained in this position when the lever is shifted in the opposite direction to respectively hold the lever in either of its two adjusted positions.

20 In operation all of the parts of the device, with the exception of the button 38, are concealed within the instrument and the hooks 13 and 14 are normally inter-engaged to hold the bellows closed. By shifting the operating button the lever 28 is rocked on its pivots 31 to engage the

25 roller 37 with the hinged end of the hook 14 and dislodge the hook from engagement with the stationary hook 13 and when so shifted the lever will remain in this position to hold the hook 14 disengaged so that the accordion may be played. 5

From the above description it is thought that the construction and operation of the invention will be fully understood without further explanation.

10 What is claimed is:

In an accordion, the combination with spaced relatively movable members constituting the ends of the accordion and the intermediate bellows, of a stationary hook adjustably secured to one of the members, a jointed hook secured to the other of said members and having a spring pressed free end interlocked with the first named hook, an operating lever having intermediate its ends a ball and socket connection with said last named member, said last named member forming an inner wall with one end of the accordion, an outer wall spaced from said inner wall and forming part of the accordion end structure, said lever having one end adapted to engage the hinged free end of the jointed hook and dislodge the hook from the companion hook when said lever is rocked on said ball as a pivot, a keeper on said outer wall, there being a slot in said keeper through which the free end of the lever projects, and is operable from the exterior of the accordion, said slot having enlarged ends, and a spring pressed stop sleeved on the lever releasably engageable selectively in said enlarged ends of the slot to hold said lever in either of its limits of pivotal movement.

30 STANLEY OLSON.
